(57) CLAIM

The ornamental design for a skin care device, as shown and described.

DESCRIPTION

FIG. 1 is a front, right, and bottom perspective view of a skin care device, showing my design.

FIG. 2 is a rear, left, and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right, and bottom perspective view of the skin care device of FIG. 1, wherein a protective case and a main body shown separately; and,

FIG. 10 is a partial enlarged view of an area labeled 10 in FIG. 9 comprising a part of a head part.

The dash-dot broken lines shown in FIGS. 9 and 10 are for the purpose of showing enlarged areas, and form no part of the claimed design.
